UNITED STATES PATENT OFFICE.

OTTO DAU, OF YUTAN, NEBRASKA.

MAIL CARRYING AND DISTRIBUTING DEVICE.

Application filed December 10, 1923. Serial No. 679,804.

To all whom it may concern:

Be it known that I, OTTO DAU, a citizen of the United States, and a resident of Yutan, in the county of Saunders and State of Nebraska, have invented a new and Improved Mail Carrying and Distributing Device, of which the following is a full, clear, and exact description.

This invention has relation to a receptacle for mail matter and has particular reference to a device for facilitating the carrying and distribution of rural mail.

In the present practice or system the postmaster sorts the mail and distributes the same to each carrier who then re-sorts the same on his routing table. When the letters, papers and other matter are sorted and placed in the respective files the carrier then ties and piles the different bundles in the proper order for delivery or distribution over his route. This necessitates double and tedious work for the carriers, occasions delay and often results in mistakes.

The present invention contemplates a device which will overcome the above recited objections and difficulties by providing a receptacle which is designed to eliminate the use of sorting and routing tables for each carrier, which eliminates the necessity of tying mail into bundles and which affords full protection to the mail matter against loss or errors in distribution.

Furthermore the invention contemplates a mail receptacle and carrying device which will occupy a minimum amount of space both during its use for the sorting and transportation of the mail.

Furthermore the invention contemplates a device of the character set forth which in case of fire admits of its instant removal without loss of the mail filed therein.

As a still further object the invention contemplates a device of the character set forth which is comparatively simple in its construction, inexpensive to manufacture and which is thoroughly reliable and highly efficient in its purpose.

With the above recited and other objects in view, the invention resides in the novel construction set forth in the following specification, particularly pointed out in the appended claims and illustrated in the accompanying drawings, it being understood that the right is reserved to embodiments other than those actually illustrated herein to the

full extent indicated by the general meaning of the terms in which the claims are expressed.

In the drawings—

Figure 1 is a plan view of the device in its unrolled or opened condition.

Fig. 2 is a fragmentary enlarged detail face view illustrating one of the strap loops and indicia card holders attached to the body of the device.

Fig. 3 is a rear view of the same prior to its assembly with the body.

Fig. 4 is a sectional view taken approximately on the line 4—4 of Fig. 2.

Fig. 5 is a fragmentary longitudinal sectional view taken approximately on the line 5—5 of Fig. 1.

Fig. 6 is a perspective view of the carrying device in rolled open condition.

Referring to the drawings by characters of reference the device comprises an elongated strip 10 preferably of canvas or any other suitable flexible material. The upper and lower ends of the canvas are preferably embraced by the binding strips 11 and 12 which are of a suitable rigid material for the purpose of holding the ends laterally distended. The upper strip 11 is formed with eyelets 13 to allow for the hanging or suspension of the device from nails or hooks on a wall or other support. To the inner face of the body or strip 10 a plurality of longitudinally spaced transversely disposed elements 14 are stitched or otherwise secured as at 15 and to the rear or inner face of said element 14 loops 16 are centrally secured. On the outer or front face of each element 14 a card holder 17 is attached. A longitudinal strap 18 is permanently secured at its upper end as at 19 to the upper end of the body or strip 10 and is trained through the loops 16 which are disposed in longitudinal alignment. The lower end of the strap is provided with perforations 20 for selective engagement with a buckle 21 attached to the inner face of the body or strip 10 adjacent its lower end. The strap 18 is preferably, although not necessarily, of an elastic material and portions of said strap and the strip or body lying between the elements 14 define embracing and retaining pockets for the reception of the mail matter M which is filed therein. Due to the fact that the strap 18 is freely slidable through the loop 16 on the elements 14, it is

obvious that the embracing and retaining pockets may be varied in size to snugly embrace and engage the matter which is filed in each pocket. The card holders 17 are designed to receive indicia bearing cards 22 which indicate the names of the individuals whose mail is to be filed in the respective pockets and the arrangement of the cards is such that the mail is properly lined up for distribution over the route to be taken by the carrier. On the inner face of each strip or body 10 suitable indicia 23 is inscribed and similar or corresponding indicia 24 is inscribed on the lower end of the outer face so that the same is clearly visible when the device is in rolled up condition as illustrated in Fig. 6. In order to maintain the device in rolled up condition a belt 25 having a buckle 26 at one end is secured or attached as at 27 to the outer side of the upper end of the strip or body 10.

In contradistinction to the present old method or system, the carrier upon his arrival from the route, after distribution, hangs the new device on the wall and is ready for filing the next day or for the next delivery. Every time a piece of mail is filed in the device it is there to stay and does not have to be touched again until it is ready for distribution. By virtue of this device the system requires only an ordinary distributing bench from which the postmaster, after sorting the mail, deliver the same to the carrier of each route who in turn files the same in the respective pockets. After the mail is filed in the pockets of the devices and the device is rolled it is amply protected from the weather and eliminates the possibility of danger of the mail blowing away or becoming wet or muddy, as the strap 18 securely holds it in the pockets defined by the strap. It will be further appreciated that by hanging the devices on the wall for filing a minimum amount of space is required. When distributing or delivering the mail en route from the device it is accomplished in the following manner: The device is laid on the seat of the vehicle next to the carrier and is unwound while distributing and rewound at the same time after the extraction of the mail from the pockets.

From the foregoing it will be obvious that an extremely simple and efficient device has been provided for facilitating the carry-

ing or distribution of mail, especially on 55 rural routes.

I claim:

1. A device for facilitating the sorting, carrying and distribution of mail comprising an elongated sheet of flexible material, 60 means at the opposite ends of the sheet for holding the same laterally distended, alined apertured portions in one end of said sheet to afford means for suspending the same vertically from a support to permit the application of the mail thereto, a longitudinally extending strap on the inner face of said sheet having a permanent connection with the inner face of the sheet at 65 on one end and an adjustable connection therewith at the opposite end, longitudinally spaced transverse strips carried by the inner face of the sheet and secured thereto at their opposite ends, guide loops on the inner face of each strip through which the strap is 70 trained to define between said strap and the sheet a plurality of adjustable mail matter embracing and retaining loops and means secured to the outer side of the sheet for holding the same in a rolled-up condition. 75

2. A device for facilitating the sorting, carrying and distribution of mail comprising an elongated sheet of flexible material, means at the opposite ends of the sheet for holding the same laterally distended, alined 80 apertured portions in one end of said sheet to afford means for suspending the same vertically from a support to permit the application of the mail thereto, a longitudinally extending strap on the inner face of said sheet having a permanent connection 85 with the inner face of the sheet at one end and an adjustable connection therewith at the opposite end, longitudinally spaced transverse strips carried by the inner face of the sheet and secured thereto at their 90 opposite ends, guide loops on the inner face of each strip through which the strap is trained to define between said strap and the sheet a plurality of adjustable mail matter embracing and retaining loops and means secured to the outer side of the sheet for holding the same in a rolled-up condition and elements 95 for the reception of indicia bearing guides relative to each receiving loop secured to the 100 outer face of each cross strip.

OTTO DAU.
